UNITED STATES PATENT OFFICE.

JAMES WILFRED CRYER AND NATHAN MANGNALL, OF BOLTON, ENGLAND, ASSIGNEES
TO WILLIAM WADSWORTH AND SONS LIMITED, OF BOLTON, ENGLAND.

BELT-DRIVING MECHANISM.

1,291,426.

Specification of Letters Patent.

Patented Jan. 14, 1919.

Application filed September 20, 1916. Serial No. 121,308.

To all whom it may concern:

Be it known that we, JAMES WILFRED CRYER and NATHAN MANGNALL, subjects of the King of Great Britain, and residents of 5 Bolton, in the county of Lancaster, England, have invented a certain new and useful Improvement in or Appertaining to Belt-Driving Mechanism, of which the following description, having reference to the accompanying sheets of drawings, is a specification.

Our invention relates to improvements in or appertaining to belt driving mechanism, particularly that type used in connection 15 with lifts or elevators. In this type of apparatus many devices have heretofore been employed for traversing the driving belts on to the fast and loose pulleys in accordance with the direction in which the cage or car is desired to travel or when its motion 20 has to be arrested, and these devices have been used in connection with mechanically operated locking means mounted in connection with the several gates guarding the well 25 of the lift for the purpose of preventing the raising or lowering of the car except when all the gates are closed. However, it has been possible in connection with the usual chain and rod controlling means, to interfere with these locking devices and for the attendant to cause the traverse of the car when one or more of the gates is or are open, while in some cases the driving belts have 30 not had transmitted to them their full movement to entirely clear them of the fast pulley at such times as they should occupy their respective positions upon the loose pulleys. For these reasons many accidents have happened to the operators or users of lifts or 35 elevators driven and controlled by this type of mechanism. Our present invention has for its object the application of electrically controlled devices for traversing the driving belts from the fast to the loose pulleys, such controlling devices being so arranged that 40 whenever either of the driving belts is moved from the fast pulley such movement is to its full extent or entirely clear of the driving pulley, and that without being directly under the control or the direction of the attendant, or in other words the attendant merely brings such devices into action and cannot directly move said driving belts. At 45 the same time that the driving belt is shifted a brake is automatically applied to the driv-

ing pulley so as to arrest the motion of the 55 car immediately. Our improvements are preferably used in combination with safety devices for the doors of the well of the lift in order that the car cannot be started into movement save when all the gates are closed, 60 although we may if desired employ our electrical moving or controlling means for the driving belts without any such safety appliances for the doors.

In order that our said invention may be 65 readily understood, we have hereunto appended sheets of drawings illustrative thereof, to which, by figures and letters, reference is made in the following description:—

Figure 1 is an elevation of our improvement 70 as seen in the direction indicated by the arrow *a*, Fig. 2, certain parts being broken away so that others may be more clearly seen.

Fig. 2 is a sectional elevation thereof 75 taken on the line C—D.

Fig. 3 is a sectional plan of a portion of said apparatus taken on line A—B.

Fig. 4 is an end elevation of the brake 80 operating bar and its weighted lever.

Fig. 5 is a front elevation of said bar.

In carrying our invention into effect, we make use of any ordinary belt driving gear for the lift or hoist, but preferably that wherein two loose pulleys 1, 2, and a fixed 85 pulley 3 are employed as shown by Fig. 1, these pulleys being mounted on a shaft in manner well known. Straight and crossed belts are used in connection with the loose pulleys 1 and 2, and one or other of these 90 driving belts is traversed on to the fixed pulley 3 by means of the belt fork *a* or *b* as desired, this reversing gear being old and well known. In Fig. 1 both of the driving belts 4, 5 are shown upon their respective 95 loose pulleys 1 and 2. The belt forks *a*, *b*, are carried respectively by the plates *a'*, *b'*, formed or fixed upon brackets *a''*, *b''*, which are fixed upon the slidable shafts *c* and *c'* their forked or guiding ends *a''*, *b''*, 100 fitting respectively over the shafts or rods *c'* and *c*. The rods or shafts *c*, *c'* take through and are supported by the bearings *d*, *d'*. The bar *c* is adjustably connected to the bell crank lever *f* fulcrumed at *f'* upon 105 the framework *F*, this lever being connected by the rod *h* with the core *k* of the solenoid *m*, the latter of which is also supported by said framework *F*.

The rod c^1 is connected to the bell crank lever f^2 fulcrumed at f^3 on the framework F^1 , the rod h^1 connecting said lever f^2 with the core k^1 of the solenoid m^1 . It will be seen 5 that on an electrical circuit being completed which includes the solenoid m , the core k will, by the aforesaid connections, cause the rod c to traverse horizontally and carry the belt 4 from the loose pulley 1 to the fixed 10 pulley 3, while on a circuit being completed through the solenoid m^1 , the rod c^1 is similarly caused to move the driving belt 5 from the loose pulley 2 to the fixed pulley 3. Counterbalancing means, such as weights n 15 return the cores k k^1 , levers f , f^2 and the belt forks a and b to their normal positions as shown by Fig. 1 immediately on the breaking of the respective circuits, and this movement will cause the belt to be moved 20 fully on to its respective loose pulley without further control by the attendant. The lever f has a rod o connected thereto by a pin and slot f^x , said rod extending to a lever r and another rod o^1 extends from the lever f^2 to 25 a similar lever at the opposite side of the apparatus, both of these levers being connected to the bar s which swivels in bearings s^1 , s^2 . The bar s has lugs s^4 extending from it through which takes a pin s^5 having loosely 30 mounted thereon the brake-shoe t , which is shown in contact with the driving pulley 3 in Fig. 2.

It will be seen that when either of the levers f or f^2 is moved by the solenoid m or m^1 , 35 the rod o or o^1 causes an oscillation of the bar s , thus moving the brake-shoe t away from the driving pulley 3, this movement of the brake shoe taking place at the end of the movement of the levers f or f^2 because of 40 the pin and slot connection f^x .

Suitable levers or arms provided with weights u are carried by the levers r connected to the rod s by which the brake-shoe t is forced firmly into contact with said driving 45 pulley 3 when either the belt guide a or b is returned by its respective counterbalancing weight or spring to its normal position illustrated by Fig. 1. The brake-shoe t and bar s are mounted to intervene between the 50 upper and lower parts of the driving belts as shown by Fig. 2.

Any appropriate switch devices may be employed to close either of the circuits containing the solenoids m or m^1 by which the 55 core may be caused to ascend or descend and the driving belt will remain on the fixed pulley 3 so long as the attendant keeps the switch (which may be termed the "car switch") in its closed position. However, 60 immediately he releases same and breaks the circuit one of the weights n will move the driving belt on to its respective loose pulley without any intervention on the part of the operator, at the same time the weighted lever 65 u will apply the brake t to the fixed pulley

3 and thus arrest the motion of the car immediately. By thus arranging the arresting of the movements of the car by the means or the method described, no interference therewith or neglect may be exercised by the 70 operator as is the case in many instances with the usual style of chain or rod or other mechanical starting and stopping devices.

Although we have hereinbefore described our means as applied to driving gear for 75 lifts or elevators, we wish it to be understood that we may apply it to belt driving gear generally.

Such being the nature and object of our said invention what we claim is:— 80

1. An improvement in belt driving mechanisms comprising a slideable shaft, a belt shifting device attached to said shaft, a bell crank lever having one arm connected with one end of said shaft and the other arm provided with means for maintaining the bell crank lever in a predetermined position, and electromagnetic means connected with the last mentioned arm of the bell crank lever for moving and holding said lever 90 away from said predetermined position. 85

2. An improvement in belt driving mechanisms comprising a slideable shaft, a belt shifting device attached to said shaft, a bell crank lever, means for adjustably connecting one arm of said lever with one end of said shaft, a weight on the other arm of said bell crank lever for maintaining the latter in a predetermined position, and electro-magnetic means connected with the 100 weighted arm of the bell crank lever for moving and holding said lever away from said predetermined position. 95

3. An improvement in belt driving mechanisms comprising a slideable shaft, a belt 105 shifting device attached to said shaft, a bell crank lever having one arm connected with one end of said shaft and the other arm provided with means for maintaining the bell crank lever in a predetermined position, 110 and electromagnetic means connected with the last mentioned arm of the bell crank lever for moving and holding said lever away from said predetermined position, a brake, and means connecting the brake and 115 the bell crank lever.

4. An improvement in belt driving mechanisms comprising a slideable shaft, a belt shifting device attached to said shaft, a bell crank lever having one arm connected with 120 one end of said shaft and the other arm provided with means for maintaining the bell crank lever in a predetermined position, and electromagnetic means connected with the last mentioned arm of the bell 125 crank lever for moving and holding said lever away from said predetermined position, a brake, and an arm projecting from the bell crank lever and having a lost motion connection with said brake. 130

5. An improvement in belt driving mechanisms comprising a pair of slidable shafts, belt shifting devices, one for each shaft, each belt shifting device having means by
5 which it is attached to its shaft and means by which it is guided by the other shaft, means engaging the respective shafts for maintaining the belt shifting device in predetermined positions, and electromagnetic means for moving the shafts to actuate the 10 belt shifting devices.

JAMES WILFRED CRYER.
NATHAN MANGNALL.
